UNITED STATES PATENT OFFICE

FRED A. LUNDAHL, OF MOLINE, ILLINOIS

VEHICLE TOY

Application filed January 8, 1928, Serial No. 611,224. Renewed September 9, 1929.

This invention relates to improvements in vehicle toys.

One object of the invention is to provide a vehicle toy made substantially entirely of sheet metal and which is very economical to manufacture and exceedingly rigid in construction and well adapted to withstand rough, hard usage.

Another object of the invention is to provide a toy miniature automobile, composed substantially of sheet metal stampings and pressings rigidly united by welding so as to produce, in effect, a one-piece unitary structure except for certain few necessary movable parts, to the end that the device is extremely durable and of attractive appearance.

Other objects of the invention relate to certain details of construction by which economy of manufacture is promoted and the rigidity and durability of the toy as an entirety is increased, as will more fully appear from the description and claims hereinafter.

In the drawings forming a part of this specification, Figure 1 is a side elevational view of a toy vehicle embodying my improvements. Figure 2 is a front end-elevational view of the toy illustrated in Figure 1. Figure 3 is a vertical longitudinal sectional view corresponding substantially to the section line 3—3 of Figure 2. Figure 4 is a vertical transverse sectional view corresponding substantially to the section line 4—4 of Figure 3. Figure 5 is a top plan view of the running gear and chassis or frame with the body and other parts removed. Figure 6 is a top plan view of a combined fender, running board and floor member made of one piece, employed in my construction. Figure 7 is a vertical transverse sectional view taken substantially on the line 7—7 of Figure 6. Figure 8 is a longitudinal detail sectional view taken substantially on the line 8—8 of Figure 6. And Figure 9 is a detail, sectional view of the braces utilized in connection with my invention taken on the line 9—9 of Figure 5.

In said drawings, the vehicle toy is shown as provided with four corner wheels arranged in a front pair 10—10 and a rear pair 11—11. The rear pair of wheels 11 is freely rotatably mounted on a rear axle 12 and held in place

by any suitable means—as for instance, by riveting over the ends of the axle 12 as indicated at 12^a. Each front wheel 10 is similarly rotatably mounted on a knuckle piece 13, the knuckle pieces 13 being pivoted upon vertically extending pivot pins 14 in turn supported by vertically spaced ears 15—15 (see Figure 3) which constitute integral flanges of the front bolster or axle housing designated generally by the reference character A. Each knuckle piece 13 is in the form of a bell crank, preferably a casting, one arm of each bell crank, as indicated at 16, being extended rearwardly, the two arms being connected by a pivotally attached link 17 which functions as the connecting rod of the steering mechanism. All four wheels 10 and 11 are also preferably in the form of aluminum castings to thereby promote lightness and obtain necessary strength.

The rear axle 12, as best shown in Figures 3, 4 and 5, is supported in sleeves 18—18 formed integral with the rear axle housing or bolster designated generally by the reference character B. The latter, at its center, is preferably provided with stamped out upwardly and downwardly extending semi-circular flanges 19—19 in order to simulate the usual differential housing of an automobile. Also formed integrally with the rear axle housing B, which is in the form of a stamped and formed sheet metal plate, are upwardly converging sections 20—20 in imitation of the common form of semi-elliptic rear axle spring. The sections 20 are merged at their tops as indicated at 20^a and the merged sections then bent horizontally forwardly to provide a flange 20^b, the latter being employed, as hereinafter explained, in attaching the chassis or frame. Also formed integrally with the rear axle housing B are two forwardly extended braces 21—21 which are bent upwardly and forwardly to the front of the vehicle where they are ultimately merged as indicated at 21^a and adapted to be welded to the frame or chassis as indicated at 21^b in Figure 5. With this construction, the rear axle housing is made extremely rigid and thereby well adapted to withstand heavy loads without danger of collapse and at the

same time it will be noted that the structure presents a pleasing appearance.

Referring now again to the front axle housing A, the latter, in addition to the knuckle supporting flanges 15, has integrally formed therewith a horizontal lower cross member 22, opposite upwardly curved integral sections 23-23 which merge as indicated at 23^a and from the merged sections are extending upwardly diverging arms 24-24, the latter, at their upper ends, having rearwardly bent horizontal flanges 24^a, to provide means of attaching the frame or chassis thereto by spot welding. Also formed integrally with said housing A are two bracing arms 25-25 which are bent from the main plane of the housing A at the bottom thereof, first horizontally as indicated at 23^a in Figure 3, thence upwardly and rearwardly as indicated at 25^b, said arms being merged with a flat cross piece 25^c adapted to be spot welded to the frame or chassis. The cross member 22 and the bracing arms 25 of the front axle housing, as are also the bracing arms 21 of the rear axle housing, are preferably made of curved cross section with the flanges turned downwardly, as best illustrated in Figure 9 of the drawings, so as to thereby obtain greater strength with respect to loads applied vertically.

The frame or chassis proper indicated generally by the reference character C, illustrated best in Figures 3, 4 and 5, preferably consists of a plate having a rectangular opening 26 cut out of the same near the front and a larger rectangular opening 27 cut out of the same near the rear. Said chassis member C is provided with a wide tongue 28 centrally disposed and projecting into the rectangular opening 27, the rear end of said tongue 28 being spot welded to the rear axle housing bracing members as indicated at 21^b in Figure 5. Said chassis member C is also spot welded to the flanges 24^a and 20^b of the front and rear axle housings A and B respectively, as heretofore described. The chassis member C is provided along each side thereof with a downturned flange 29, the latter being oppositely and inwardly inturned as indicated at 29^a, best in Figure 4. By this construction, great strength is obtained in the chassis member C with respect to vertically applied loads. Additional strength is also obtained by forming a vertical transverse flange 30 across the rear edge of the opening 27, as best illustrated in Figure 3.

The combined fender, running board and floor member, is indicated broadly by the reference character D, the same being best illustrated in Figures 6, 7 and 8. Said member D is first stamped or cut from a flat plate to the proper configuration and is then shaped or bulged by suitable dies so that, in its finished form, said member D comprises a relatively elongated flat floor 31 and on each side thereof an arcuate flanged front wheel

fender 32 and arcuate flanged rear wheel fender 33 connected by an intermediate integral horizontal running board 34. In forming the front wheel fenders, the metal is sloped upwardly and outwardly as indicated at 32^a and between the floor 31 and the running boards 34, the sheet is bent downwardly and outwardly, as indicated at 34^a. Rearwardly of the floor section 31, the metal sheet is cut out to provide a rectangular opening 35, the metal at the sides of said opening being flanged vertically upwardly as indicated at 36-36 and thence bent inwardly as indicated at 36^a-36^a to form horizontal flanges for the box shown and hereinafter described. At the rear end, the member D is so formed as to close the rear end of the rectangular opening 35 by oppositely inturned horizontal wide flanges 37-37, which have their edges abutting as indicated at 37^a in Figure 6. Said flanges 37 are so located as to rest upon and be spot welded to the rear transverse section 38 of the chassis member C.

For the rear wheel fenders 33, I preferably employ additional inner skirt pieces 39 which fit within and are spot-welded to the fenders proper 33. Each of said skirt pieces 39 has an inwardly extended flange or arm 40, as best shown in Figures 6 and 7. With the exception of the skirt pieces 39, it will be observed that all four wheel fenders, running boards and floor, are formed integrally, thus obtaining a member which is unusually strong and adapted to resist rough usage. In this particular connection, while I have shown the member D as forming a part of a toy vehicle, nevertheless, a similar member may be made upon a large enough scale to be employed in commercially usable vehicles with a saving in cost of manufacture as well as an increase in efficiency and durability, as compared with the present practice employed commercially on full size automobiles.

The body member of the toy vehicle, as shown, except for certain superstructure and the radiator, as hereinafter explained, also consists of a single sheet of metal, said body member being designated generally by the reference character E. Said body member E, in its finished form, has a rounded back wall 41 and side walls 42 with imitation doors 43 pressed therein. Forwardly of the side walls, said body member E has the sides thereof converged forwardly as indicated at 44 and the top 45 sloped downwardly slightly. In this connection, as will be apparent from an inspection of the drawings, said body member E is made in outline to simulate the outlines of a well known type of vehicle so as to present a pleasing appearance. The forwardly converging sides 44 are preferably provided with louvers as indicated at 46 in imitation of the usual louvers found on the full size commercial vehicle. The radiator 47 is a separate stamping having inturned flanges 130

around the edges thereof as indicated at 47^a, which are fitted within the front end of the hood portion made integral with the body and spot welded thereto. At the top, at the center, said radiator member 47 has the top flange 47^b thereof bent over a cross piece 48 and thence under the metal of the hood, as best shown in Figure 3.

The combined body and hood member E is formed as follows. A flat plate or blank is first taken and then cut to the proper configuration. The cut blank is next formed so as to provide a curved back wall 41 and bent at the corners of the back wall as indicated at 41^a in Figure 3 so as to bring the sides 42 into their proper plane. During this forming operation, the door indentations are made and the necessary necking in where the hood merges with the body proper, is also performed as well as the bending along the hood corners 49—49. The edges of the thus formed body and hood blank are welded with an edge butt joint along the line as indicated at 50 in Figure 2. With this arrangement, I provide a one-piece body and hood structure which is very economical to manufacture, pleasing in appearance and possessing unusual durability.

The seat of the toy vehicle is provided by a separate member F having a slightly curved approximately horizontally extending seat portion proper 51 and vertically extending front wall 52. The seat portion 51 has a flange along the rear edge thereof as indicated at 51^a which is spot welded to the back wall 41 of the body member. The front wall 52 of the seat is flanged along its lower edge as indicated at 52^a, said flange 52^a being spot welded to the floor 31 of the fender member D.

The canopy for the body is formed by a top member G, two triangular side members H—H and a combined windshield and instrument board member J. The top member G has a horizontal top portion proper 53, a sloping front portion 54, vertical side flanges 55, and a rear or back wall 56, the latter having an opening 57 cut therein, surrounded by suitable beading 58 in imitation of the usual window. Each of the triangular side members H has a vertically extending corrugated post 59, diagonally extending corrugated strut or brace 60, and a top cross beam 61, the latter being spot welded to the under faces of a side flange 55 of the top member G. The posts and struts are merged at their lower ends into a flange 62 which is spot welded to the inner side of the body member adjacent a corner of the pressed-in doors.

The combined windshield and instrument board member J has a top horizontally extending section 63 which is suitably flanged as indicated at 63^a so as to fit within and be spot welded to the front edge of the top member G. Said member J has vertically extending corrugated side posts 64 and right angu-

lar bottom cross beam 65 which rests upon the cowl of the hood and is spot welded thereto. A rectangular opening 66 is left in said member J in imitation of the usual glass windshield proper. Along the bottom, said member J is formed with a downwardly and rearwardly sloping horizontally extending wide flange 67 in imitation of the usual instrument board, said flange 67 being provided with an outwardly and downturned narrow flange 67^a to provide the necessary rigidity.

In the drawings, I have illustrated the rear of the toy vehicle as equipped with a box indicated broadly by the reference character K. Said box has a bottom 68, vertically extending side walls 69, and front wall 70 fitting against and spot welded to the back wall 41 of the body E. Said side walls 69 of the box are flared outwardly along their top edges as indicated at 69^a. At the rear end, the floor 68 is doubled back upon itself as indicated at 68^a so as to obtain greater strength and minimize tendency to bulge. The rear end of the box is closed by a pivoted tail board 71 which is adapted to fit between the side walls 69 as best shown in Figure 4 and which is also provided, at each top corner thereof, with a laterally extended hook-shaped flange 71^a, the latter being arranged to drop or hook within correspondingly located slots 72 in the flanges 69^a. The hinges for the tail board 71 are formed integrally therewith and consist of tangs 73 which are bent so as to provide loops as best shown in Figure 3, said hinge loops passing through suitable slots 74 in the doubled-over edge 68^a of the box. The hinge loops 73, as clearly shown in Figure 3, are made sufficiently large to permit the hook flanges 71^a being disengaged from the slots 72, when it is desired to drop the tail board. With this construction, not only do I obtain an efficient, economical and durable pivotal mounting for the tail board but in addition, it will be noted that the tail board, when in operative position, serves effectively to prevent spreading of the side walls of the box on account of the hook flanges 71^a, as will be clear from an inspection of Figure 4.

In order to steer the toy vehicle, I provide a hand wheel 75 rigidly secured to the upper end of the downwardly and forwardly sloping steering post 76 which is extended through a suitable opening 77 provided in the instrument board, said opening 77 also providing one bearing for the steering post 76. The steering post 76, near its lower end, is extended through a slightly elongated opening 78 in the floor of the fender member D, (see Figure 6) and by which another bearing is obtained. At its lower end, the post or shaft 76 is bent approximately at right angles to provide a crank arm 79, the lower end of the latter entering at an angle, a rectangular opening 80 formed in a flange integral with the connecting rod 17 of the steering wheels. By refer-

ring to Figure 3, it will be seen that the two bearings provided at the openings 77 and 78 prevent the steering post 76 from moving laterally of the vehicle and after the crank arm 79 is entered within the opening 80, the steering post cannot be moved axially in either direction so that I thus provide a very simple and economical method of mounting the steering post and one which cannot become disassembled after the parts of the vehicle have been properly united, except by distortion of some part. As will be obvious, upon rotation of the steering wheel 75, the front wheels 10 will be shifted to correspond so that the vehicle may be readily steered.

In assembling the parts of the vehicle, the chassis or frame member C, before the body or any other part above is applied thereto, is spot welded to the front and rear axle housing assemblies at the points heretofore described and in this connection, it will be observed that the spot welds will always occur where there are only two thicknesses of metal. After the combined body and hood member E is formed as heretofore described, the front wall 70 of the box K is spot welded to the rear wall 41, there being only two thicknesses of metal where the spot welds occur. Thereafter, the seat F is spot welded to the body member E, at points along the flange 51^a. This assembly of the body member E, seat F, and box K is then spot welded to the combined fender and running board member D, the spot welds for the seat F occurring with 35 in the flange 52^a and for the body and hood portions in inturned flanges 42^a and 44^a (see Figure 3). The bottom 68 of the box is spot welded to the flanges 36^a (see Figure 7) of said member D. Again, it will be noted that all of the spot welds occur where they are only two thicknesses of metal.

The spot welded assembly of members D, E, F and K, above described, is then spot welded to the chassis member C, these spot welds being made between the floors 31 of the member D and that portion of the member C which is left between the openings 26 and 27 (see Figure 5). The spot welding last mentioned, also occurs where there are only two thicknesses of metal. The canopy or top member G, side frames H and windshield member J are obviously adapted to be spot welded to each other and to the body member at points where only two thicknesses of metal occur.

From the preceding description, considered in connection with the drawings, it will be seen that the completed vehicle toy, except for such parts as are necessarily movable, comprises what may be termed a rigid unitary or one-piece structure with the sections of metal efficiently located so as to obtain great strength under vertical loads. It will also be noted that by forming the parts as described in detail, all spot welds are made

where only two thicknesses of metal occur, which is of extreme importance both in facilitating the spot welding operations and also in insuring that the spot welds are properly made without danger of burning any of the metal, which would occur if the spot welds were attempted to be made at points where three or more plies of the sheet metal occur.

Although I have shown and described a box, suitable for carrying small articles such as children would play with, it will be understood by those skilled in the art, that I might substitute a structure similar to the usual design of tonneau used on commercial full size vehicles, without departing from the spirit of the invention. As hereinbefore mentioned, the structure of the combined fender and running board member D is adapted for full size vehicles, but I am also aware that the improved combined body and hood member E and the process of making the same, herein described, may also be employed on full size vehicles by using dies of proper size.

I have herein shown and described what I now consider the preferred manner of carrying out the invention, but the same is merely illustrative and I contemplate all changes and modifications that come within the scope of the claims appended hereto.

I claim:

1. In a toy vehicle having front and rear axles and front and rear pairs of wheels, the combination with a suitable frame and body; of front and rear sheet metal axle housings, each housing having also formed integrally therewith, upwardly extending stamped sections corresponding to front and rear transversely disposed semi-elliptic spring suspensions and on which suspensions, sections of the vehicle frame are adapted to be supported.

2. As an article of manufacture, a one-piece member for vehicles having bulged portions providing front and rear wheel fenders connected by an intermediate running board on each side thereof, a centrally disposed floor section at the forward end of said member, and an off-set rear frame extension adapted to provide a support for a superimposed part of the vehicle.

3. As an article of manufacture for automobiles, a one-piece sheet metal combined body member and hood, said member having a continuous back wall, side walls bent forwardly of the side edges of the back wall, and oppositely disposed integral extensions on the forward portions of the side walls, said extensions being bent inwardly to form the hood, the inner edges of said extensions being rigidly united by a seam extending lengthwise along the top of the hood.

4. In an automobile toy having front and rear axles and front and rear pairs of wheels, the combination with a suitable frame and body; of front and rear sheet metal axle hous-

ings, each housing having formed integrally therewith, upwardly extending stamped sections corresponding to front and rear transversely disposed semi-elliptic spring suspensions respectively, and integrally formed diagonally inclined braces, said frame being adapted to be rigidly united to the upper portions of said stamped spring suspensions and said braces.

5. In a vehicle toy having front and rear axles and front and rear pairs of wheels, the combination with front and rear axle bolsters; of an integral chassis extending between and supported on said bolsters, said chassis having a flat top, integral downturned flanges along the sides thereof, and integral inturned flanges on the lower edges of said first named flanges.

6. In a vehicle toy, the combination with a body, supporting frame, and front and rear bolsters; of a box supported on said frame, said box being comprised of sheet metal and having a bottom, upwardly extending side walls bent outwardly along their top edges; and a tail board having an integrally formed looped tang extended through an opening in the floor of the box by which the tail board is pivotally attached, said tail board, at the top corners thereof, having hook flanges and the corresponding portions of the outwardly bent side walls having openings to receive said hook flanges whereby, when the tail board is in operative position, said tail board serves to prevent spreading of the box side walls.

7. An automobile toy comprising, in combination: sheet metal front and rear bolsters; a sheet metal chassis supported on said bolsters; a sheet metal body and hood mounted on said chassis; a box secured to said body and supported from said chassis, said box being made of sheet metal and having a bottom horizontal wall, upwardly extending side walls bent outwardly along their top edges, said bottom being doubled back upon itself along the rear edge thereof and provided with openings through the doubled-over edges; and a sheet metal tail board of a contour to fit between the side walls of the box, said tail board having integral looped tangs extending through said openings and by which a loose pivotal connection for the tail board is obtained, the tail board, at its top corners, having oppositely extending hook flanges and the outturned upper edges of the side walls having corresponding openings to receive said hook flanges.

8. An automobile toy comprising, in combination: front and rear sheet metal axle housings having integrally formed spring suspension sections; a sheet metal chassis supported at its front and rear ends by said axle housings and welded thereto; a sheet metal member superimposed upon said chassis and having front and rear fenders, a floor

section, and running boards integrally formed; a one-piece combined sheet metal body and hood secured to said fender member; a sheet metal canopy secured to said body member; a combined windshield and instrument board sheet metal member secured to said canopy and the body member; and means for steering the front wheels of the automobile.

9. A toy automobile having a chassis in the form of a rectangular frame including a plate portion extending between the side members of the said frame; of axle housings having spaced rigid connections with said plate portion of said chassis; an integral fender member having front and rear fenders, and running boards connected thereto, and having a central floor section extending between said running boards and fenders; a hollow body member having an open bottom portion, said opening being defined by turned flanges, the flanges of said body member being welded to the central floor section of said fender member, and said central floor section being disposed upon said chassis with the portion closing the opening in the body member resting upon the plate portion of the chassis, said plate portion of the chassis between the spaced rigid connections of the inner portions of the axle housings being secured to the portion of the fender member which closes the opening in said body member by welded connections.

10. A toy automobile having a chassis in the form of a rectangular frame including a plate portion extending between the side members of said frame; of axle housings, having portions welded to the plate portion of said chassis, the points of the welding of the housings to said plate being spaced apart; a fender member having front and rear fenders and running boards connected thereto, and having a central floor section extending between said running boards and fenders; a hollow body member having an open bottom portion, said opening being defined by turned flanges, the flanges of said body member being welded to the central floor section of said fender member, said body member being provided with a seat having a turned flange welded to said central floor section, said central floor section being disposed upon the chassis, with the portion closing the opening in the body member resting upon the plate portion of the chassis, said plate portion between the spaced welded connections of the axle housings being secured to the portion of the fender member closing the opening in said body member by welded connections.

11. A toy automobile having a chassis including a plate portion extending between the side members thereof; of axle housings, said housings having spaced welded connections with the plate portion of said chassis; a fender member having front and rear

members and running boards connected thereto and having a central floor section extending between said running boards and fenders, said fender member having also a rear frame extension comprising turned flanges offset from the body of said fender member; a superposed part of the vehicle supported by said flanges and welded thereto; a hollow body member having an opening in its bottom, said opening being defined by turned flanges, the flanges of said body member being welded to the central floor section of said fender member, and said central floor section being disposed upon said chassis with the portion closing the opening in the body member resting upon the plate portion of the chassis, said plate portion between the spaced welded connections of the inner portions of the axle housing, and forwardly of said superposed part, being secured to the portion of the fender member closing the opening in said body member by welded connections.

12. In a toy automobile, the combination with a chassis; of axle housings secured to each end of said chassis; a one-piece fender member mounted on said chassis, having front and rear fenders and running boards connected thereto and having a central floor section extending between said running boards and fenders, said fender member having also a rear frame extension including turned flanges offset from the body of said fender member; and a superposed part of the vehicle supported by said flanges and welded thereto.

13. In a toy automobile, the combination with a chassis including a plate portion extending between the side members thereof; of axle housings rigidly secured to the forward and rear ends of said chassis; a one-piece fender member mounted on said chassis and having front and rear fenders and running boards connected thereto, and having a central floor section extending between said running boards and fenders, said fender member having also a rear frame extension comprising turned flange portions offset from the body of said fender member; a superposed part of the vehicle supported by said flange portions and welded thereto; a hollow body member having an opening in its bottom, said opening being defined by turned flanges, the flanges of said body member being welded to the central floor section of said fender member, and said central floor section being disposed upon said chassis with the portion closing the opening in the body member resting upon the plate portion of the chassis, said plate portion, forwardly of said superposed part, being secured to the portion of the fender member closing the opening in said body member by welded connections, said superposed part having a

turned flange welded to the adjacent hollow wall of said body member.

14. In a toy vehicle having two axles and two pairs of wheels, the combination with front and rear axle bolsters; of a unitary longitudinally extending frame supported on said bolsters; a unitary member having a front pair of fenders, a rear pair of fenders and running boards; and a unitary body mounted on said member, said bolsters, frame, body and member forming superposed plies of material, the material in the superposed plies being cut out and arranged to provide two thicknesses of material at a plurality of different points, the points where two thicknesses of material occur being connected by welding. 70

15. In a toy, the combination with a wheeled frame; of a box supported on said frame including a bottom wall and side walls; and a tail board having a looped tang secured thereto and extending through an opening in the bottom wall of said box and serving to pivotally and slidably secure said tail board to said box; and means on said tail board engageable and dis-engageable with means upon said box upon combined pivotal and sliding movement of said tail board as permitted by said looped tang. 85

16. In a vehicle toy, the combination with a wheeled supporting frame; of a box mounted on said frame, said box being comprised of sheet metal having a bottom wall and upwardly extending side walls, the latter being bent outwardly along their top edges to provide inclined portions, said portions each having an opening therein; and a tail board having looped tangs extended through openings in the bottom wall of said box by which said tail board is loosely pivoted to said box; and angularly extending members upon the upper edge portions of said tail board adapted for insertion and removal with respect to the openings in said inclined portions as permitted by the loose pivotal connection of said tail board with said box. 95 105 110

17. In a vehicle toy, the combination with a wheeled supporting frame; of a box body supported on said frame, said body being comprised of sheet metal and having a bottom wall and upwardly extending side walls bent outwardly along their top edges to provide inclined portions, said portions each having an opening therein; and a tail board having looped tangs extended through openings in the bottom wall of said body by which said tail board is loosely pivoted to said body; and hooked integral flanges on the upper edges of said tail board adapted for insertion and removal into the openings into said inclined portions as permitted by the loose pivotal connection. 115 120 125

18. In a vehicle toy, the combination with a supporting frame having front and rear pairs 130

of wheels; a front axle and a rear axle for said wheels; and a stamped sheet metal member secured to said toy and disposed along said rear axle, said member having an enlarged central portion formed therein to simulate a differential housing for said rear axle.

19. In a vehicle toy, the combination with a supporting frame, having front and rear pairs of wheels; a front axle and a rear axle upon which said wheels are mounted; and a stamped sheet metal member disposed along said rear axle, said member having an enlarged central portion formed to simulate a differential housing for said rear axle, the portions of said member at either side of said central portion being bent about said rear axle and having its end portions secured to said vehicle.

20. As an article of manufacture, a sheet metal stamping adapted for use with the rear axle of a toy vehicle comprising an enlarged central portion formed to simulate a differential housing, and inclining attenuated extensions at either side of said central portion adapted for connection to the toy.

21. In a vehicle toy, the combination with a supporting frame including a rear pair of wheels; a rear cylindrical axle for said wheels; and a stamped sheet metal member having an enlarged central portion simulating a differential housing for said rear axle, and provided with integral extensions providing tubular sleeves disposed about said axle, said sleeves being connected to the frame of said vehicle.

22. In a wheeled toy, of the character described the combination with a frame having a front and rear pair of wheels; of a front axle rigidly secured to said frame, said axle having its opposite end portions provided with integral spaced flanges; and steering knuckles pivotally mounted in the ends of said front axle between said spaced flanges, each of said steering knuckles comprising a hub upon which the wheel is mounted, an arm for connection with a connecting rod, and an arm extending forwardly of said axle and provided with an eyelet for the reception of a member by which the vehicle may be drawn.

23. In a toy, the combination with a wheeled frame; of a box supported on said frame, including a bottom wall and side walls; a tail board for said box; means connecting said tail board to said box, said means having elements permitting swinging movement of said tail board with reference to said box, and limited shifting movement of said tail board edgewise with respect to said box; and means co-operating with said tail board and said box, adapted to maintain said tail board against swinging movement when in engagement, and being detachable by movement of said tail board edgewise with respect to said box.

24. In a vehicle toy, the combination with

a supporting frame, said frame being elongated and made up from a sheet metal plate, and having its longitudinal edges bent substantially at right angles to the remainder of said plate, and said plate being cut out adjacent one end, and cut out adjacent the opposite end a less extent, there being a web intermediate the cut-out portion of a cowl surmounting said frame above the smaller cut-out portion thereof; a body surmounting said frame above the rear cut-out portion thereof; a seat member supported by the web intermediate the cut-out portions of said frame; and front and rear wheels for said vehicle.

25. In a toy of the character described, the combination with a supporting frame, comprising an elongated substantially rectangular sheet metal plate having angular flanges extending along its longitudinal edges, and having spaced cut-out portions in the web thereof, providing a supporting web intermediate the ends of the frame, said frame having elements thereon extending along longitudinal margins of one of said cut-out portions and disposed angularly with reference to said frame, and in a direction opposite to the longitudinal edge flanges thereof; a body for said vehicle adapted to be supported by said longitudinally extending elements at one side of the main plane as defined by the web of said frame; a seat portion supported by said web; a cowl surmounting said frame above the other cut-out portion thereof; and front and rear wheels for said vehicle.

In witness that I claim the foregoing I have hereunto subscribed my name this 3rd day of January, 1923.

FRED A. LUNDAHL.
